UNITED STATES PATENT OFFICE.

JAMES AUSTIN, OF BROOKLYN, NEW YORK.

TRACTION-WHEEL.

SPECIFICATION forming part of Letters Patent No. 269,990, dated January 2, 1883.

Application filed July 6, 1882. (No model.)

To all whom it may concern:

Be it known that I, JAMES AUSTIN, of Brooklyn, Kings county, New York, have invented new and useful Improvements in Traction-Wheels, of which the following is a specification.

My invention consists of a contrivance designed to enable the wheel to travel on feet projecting from the rim, so as to take better hold for traction than the rim does, and take its load along with as little power as possible, the object being to provide apparatus of a more practical and reliable character than heretofore employed for the purpose, as hereinafter more fully described, reference being made to the accompanying drawings, in which—

Figure 1 is partly a side elevation and partly a sectional elevation in the plane of the rim of the wheel. Fig. 2 is a section of the wheel in the plane of the axis. Fig. 3 is partly a side elevation and partly a longitudinal sectional elevation of one of the toothed segments of the wheel. Fig. 4 is a plan view of Fig. 3. Fig. 5 is an end elevation of one of the feet. Fig. 6 is partly a side elevation and partly a sectional elevation of the foot represented in Fig. 5. Fig. 7 is partly a side elevation and partly a section of another form of foot, and Fig. 8 is a transverse section of Fig. 7.

I make a rim, *a*, of cast-metal segments, which have spoke or leg sockets *b*—say one to each segment and in the middle thereof—also a line of internal cog-teeth, *c*, and also an internal tread, *d*, along the sides of the cog-rim, the said cog-rim and tread being a little to one side of the line of the spoke-sockets, but as close thereto as may be without interference one with the other. Practically the spoke-sockets are cast in the form of bosses on the sides of the segments. These segments are arranged and connected together in any approved way of connecting the ends, and, forming a complete circle, are also provided with or have attached to them a broad thin rim or tire, *e*, of metal or iron plate, which at its edges is strengthened with angle-bars *f*, to which annular side plates, *g h*, are attached for partly inclosing the cog-rim and other parts to protect them from the dust, but more particularly to give the requisite stiffness to the wheel for great propelling-power, the said arrangement being adapted for affording the greatest

strength with the least metal, besides affording the basis for wholly inclosing the interior of the wheel by the application of a disk to the outside, which may be fastened on tightly, and by a cover of leather, rubber, or other flexible material to the inside, with perforations for the shafts and other connections, and contrived to pack in any suitable way, with the grooved flange *i* formed around the central opening of ring *h* for the purpose. The wheel-rim thus made and provided with feet *j* and *k*, or either kind alone or others, is to be made to revolve around the stationary circular rim or rail *u*, permanently attached to the boiler *l* or other part of the truck, and to propel the truck through the medium of said rail, the power being applied to the toothed rim by a toothed drive-wheel, *m*, to which the engine is to be geared by a chain belt working on the toothed pulley *n* or other approved means, and the wheel-rim being carried by the said toothed wheel *m*, which is also a carrier-wheel, and the two other carrier-wheels, *o* and *p*, running on the ways *d* of the segmental rim, and being mounted on axles *q*, *r*, and *s*, on which the boiler or other part of the body is suitably mounted. The ways *d* of the segments rise above the base of the teeth *c* to form strengthening-flanges to them, and so that the teeth of the driving-wheel *m* will, by extending below said flanges, serve to control the wheel-rim laterally, and the carrier-wheels *o* and *p* are grooved in the face to allow the teeth of the segmental rim to run in them for the same purpose.

The rail *u*, on which the weight of the truck is to be carried by means of the feet, is securely attached to the boiler or other part of the truck by the bar *v*, connected to it at its ends, and by bars *y*, *z*, and *z'*, and being itself connected to the boiler by the strong central stud, *w*, besides the said rail being fitted on the shafts *q*, *s*, and *r* by bearings *x*. The bars *y* and *z*, connecting the rail *u* and the supporting-bar *v*, are mainly located on the lower part of the rail, because it is there that the stress of supporting the load is mainly delivered upon it by the feet, said feet being attached to legs *a'*, projecting through the rim *e* of the wheel, also through the sockets *b*, and connected with roller-heads *b'*, carried by guiding-stems *c'* in brackets *d'*, attached to annular

ring g , said heads carrying rollers e' on suitable pivots, said rollers running on the face of the rail u , so that the weight of the load is borne on said rail, and the rail is borne on the 5 feet passing under it.

Two guide pins or rods, c' , are herein represented to each roller-head, for preventing the head from turning out of line, and in this case the said guide-rods are represented as attached 10 to said head and sliding in the brackets d' ; but it is evident that they may be attached to the brackets and fitted in the roller-heads for them to slide on the rods. I prefer the arrangement shown.

15 The rail u has a reverse curve, f' , at the bottom, the object of which is to vary the length of the radial line of the bearing-foot from the time the foot takes the load in advance of the axis until it escapes from the load at the rear 20 of said axis, and thus enable the machine to advance in a level plane instead of in a rising and falling course, as it would were it not for said curve. The length of said curve is such that the roller of one foot will pass onto it and 25 take the load on it when the roller previously sustaining the load is passing from said curve at the rear. Except when passing under rail u at f' , the rollers e' travel idly around the rail to the front of the wheel for successive opera- 30 tion.

The foot which I prefer to make consists of a hollow box made in two parts, $g' h'$, and end covers, o' , and bolted together by flanges i' , said box having a flat bottom, j' , and containing a 35 round head, k' , secured to the end of leg a' crosswise of it, said box being fitted to the head so as to turn or oscillate and also to slide lengthwise on it to a certain extent. The object of having the box turn on the head is to enable 40 it to descend flatwise on the ground, as indicated in Fig. 1, in case it may be wanted to do so, and the object of sliding lengthwise is to enable the wheel to have lateral motion on the foot in case of need when turning around short 45 curves. The head has a socket, l' , in each end, in which a spring, m' , is fitted to bear against the end of the box and shift the box back to its central position after the foot has lifted from the ground.

50 If it may be desired to prevent the foot from descending flatwise on the ground, as above described, the spring may have its ends secured, the one in the end of the box at n' and the other in the bottom of the socket of the 55 head, to oppose its torsional resistance to the turning of the foot by gravitation or otherwise, and thus insure the radial direction of the foot until the load passes onto it. The covers o' of the ends of the box will be bolted on, as shown 60 at p' , or in any other approved way. The length of the box of the foot is designed to be equal to the breadth of the wheel; but it may be more or less, as preferred. Another form of foot which I propose to use alternately with 65 the foot above described, and may in some cases use alone, consists of the foot k , securely attached to the leg a' crosswise of the rim of

the wheel, and having a groove, r' , along the middle portion of the bottom and a slot, s' , through it each side of the central boss to 70 which the leg is connected for the connection of a calk, t' , by the bit of the calk fitting in the groove r' , and with bars extending up through slots s' sufficiently to receive pins or rivets through them, over the top of the foot, to secure the calk. The foot j has an opening, w' , in the top of the cap h' of sufficiently large size to allow room for the leg in the play of the foot on the head k' and said cap; also, the foot k and the leg-sockets b have collars x' , to 80 which rubber, leather, or other suitable leggings, y' , are to be firmly bound with wire, to exclude the dust from the leg-sockets b and from the interior of foot j .

The center stud, w , connecting the bar v with 85 the boiler or truck, is provided with a stay-brace, a^2 , and a stay-rod, b^2 , connects the two arms of the said brace across the angle formed by them above center stud, w .

Having thus described my invention, what I 90 claim, and desire to secure by Letters Patent, is—

1. The combination, with the traction-wheel rim $e f g$ and a toothed rim, a , working on rollers $m o p$, substantially as described, of a series 95 of feet, $j k$, legs a' , rollers e' , and a stationary rail, u , substantially as described.

2. The combination, in a traction-wheel, of the rim $e g h$, carrying leg-sockets b , feet $j k$, and rollers e' , with stationary rail u , said stationary rail having reverse curve f' along the bottom where the load is supported on the rollers by said stationary rail, substantially as described.

3. The toothed segmental rim a , having leg- 105 sockets b , in combination with legs a' , feet $j k$, roller-heads b' , guides $c' d'$, rollers e' , and the stationary rail u , substantially as described.

4. The combination, with wheel-rim $e g h$, having leg-sockets b , and with stationary rim 110 u , of feet $j k$, legs a' , roller-heads b' , guides $c' d'$, and rollers e' , substantially as described.

5. The roller-heads b' , having two guide-rods, c' , and a pivot for roller e' , said rods being fitted in the guide-brackets d' , and said heads 115 having a leg, a' , and a foot attached thereto, substantially as described.

6. The combination of grooved flange i with the annular ring h of the inside of the wheel, 120 substantially as described.

7. The combination, in a traction-wheel, of feet j and k , arranged alternately thereon, substantially as described.

8. A foot for traction-wheels, consisting of box $h' g'$, and p' and head k' , combined and arranged with leg a' , substantially as described.

9. The combination, in a foot for traction-wheels, of the box $h' g'$ and the head k' , said box being capable of sliding and turning on said head, substantially as described.

10. The combination of springs m' with a foot for traction-wheels, consisting of a head, k' , and a box, $h' g'$, said box being capable of sliding on said head, substantially as described.

11. A foot for traction-wheels, consisting of a head, k' , and a box, $h' g'$, fitted thereon for sliding and turning, as described, and containing springs m' to adjust the box on the head laterally, said springs having the ends n' connected respectively to the head and the box, substantially as described.
12. The combination, with a traction-wheel, of feet constructed in parts arranged to allow

the wheel to shift laterally on the part of the 10 foot resting on the ground and supporting or partly supporting the load, substantially as described.
